UNITED STATES PATENT OFFICE

102,439

DESIGN FOR A COMBINED FILLER CAP AND GAUGE HOUSING

William M. Mulcahy and George E. Ford, Rochester, N. Y., assignors to Rochester Manufacturing Co., Rochester, N. Y.

Application October 12, 1936, Serial No. 65,270

Term of patent 7 years

To all whom it may concern:

Be it known that we, William M. Mulcahy, a citizen of the United States, and George E. Ford, a citizen of Canada, both residing at Rochester, in the county of Monroe and State of New York, have invented a new, original, and ornamental Design for a Combined Filler Cap and Gauge Housing, of which the following is a specification, reference being had to the accompanying drawing, forming a part thereof.

Figure 1 is a top plan view of the combined filler cap and gauge housing showing our new design.

Figure 2 is a side elevation thereof.

Figure 3 is a front elevation thereof looking in the direction of the arrow in Figure 2.

We claim:

The ornamental design for a combined filler cap and gauge housing, as shown.

WILLIAM M. MULCAHY.
GEORGE E. FORD.
